WALL ORNAMENT

Filed May 20, 1929

FIG. 1

FIG. 2

INVENTOR
E. G. WILLIAMS
BY J. G. Cook
ATTORNEY

UNITED STATES PATENT OFFICE

ELLA GERTRUDE WILLIAMS, OF ST. LOUIS, MISSOURI

DESIGN FOR A WALL ORNAMENT

Application filed May 20, 1929. Serial No. 31,307. Term of patent 7 years

To all whom it may concern:

Be it known that I, ELLA GERTRUDE WILLIAMS, a citizen of the United States of America, residing in the city of St. Louis, in the State of Missouri, have invented a new, original, and ornamental Design for a Wall Ornament, of which the following is a specification, reference being had to the accompanying drawing, forming a part thereof.

Fig. 1 is a front elevation of a wall ornament, showing my new design.

Fig. 2 is a side elevation of a wall ornament, showing my new design.

I claim:

The ornamental design for a wall ornament, as shown.

ELLA GERTRUDE WILLIAMS.
